[57] CLAIM

The ornamental design for a swabbing stick, substantially as shown and described.

DESCRIPTION

FIG. 1 is a top plan view of a swabbing stick showing my new design;

FIG. 2 is a front elevation thereof;

FIG. 3 is a side elevation thereof;

FIG. 4 is a top plan view of a second modified embodiment of the swabbing stick illustrated in FIG. 1;

FIG. 5 is a front elevation thereof;

FIG. 6 is a side elevation thereof;

FIG. 7 is a cross-section taken on line 7—7 of FIG. 2;

FIG. 8 is a bottom plan view of a third modified embodiment of the swabbing stick illustrated in FIGS. 1 and 7;

FIG. 9 is a bottom plan view of a fourth modified embodiment of the swabbing stick illustrated in FIGS. 1 and 7; and

FIG. 10 is a bottom plan view of a fifth modified embodiment of the swabbing stick illustrated in FIGS. 1 and 7.
